United States Patent Office.

DANIEL AGNEW, OF VINCENNES, INDIANA.

Letters Patent No. 97,852, dated December 14, 1869.

IMPROVEMENT IN SAW-SETS.

The Schedule referred to in these Letters Patent and making part of the same

To all whom it may concern:

Be it known that I, DANIEL AGNEW, of Vincennes, in the county of Knox, and State of Indiana, have invented a new and improved Saw-Set; and I do hereby declare that the following is a full, clear, and exact description thereof, which will enable others skilled in the art to make and use the same, reference being had to the accompanying drawings, forming part of this specification.

The nature of my invention is to obtain a saw-set of simple construction, which may be adapted for setting the teeth of either large or small saws, and capable of being readily operated.

Saw-sets have been made, previous to my invention, where the short arm of the lever operates simultaneously with the levers that operate the dies. In my invention, the short-arm levers operate independently of the others, thus making any angle on the teeth that necessity requires, or that may be desirable, separate and independent of the levers that operate the dies.

To enable those skilled in the art to fully understand and construct my invention, I will proceed to describe it, viz:

A B represent two levers or arms, having, at their outer ends, dies a b, the die b pivoted to the short-arm lever C, and working in the recessed or slotted arm A.

The slot f is made somewhat larger than the die b, to give it free and easy movement.

B is the lever-arm of the die b, and has, at one end, ears or projections, g g, which support and hold the short-arm lever D.

i is the spring, which works between the levers B and D, and assists in keeping open the lever C, and away from the saw after its operation.

The recessed or slotted lever A is operated in the ordinary manner, having a spring, j, to force the arms

apart, after gripping the saw, said spring being riveted or fastened in any desired manner to either arms.

The lever or arm B has, at one end, ears or projections g g, which form a clamp for the spring i.

h h are chain-links, so arranged, in connection with levers C and D, as to operate them independently of levers A and B.

The outer end of lever C is curved in hook-form, as shown at l, said hook extending beyond and over the dies a b.

On the short-arm lever C, are projections c c, which receive the die b, operated by lever or long arm B.

K is a thumb-screw or stop, to regulate and adjust the lever C, operated by lever D, to the thickness of the saw.

This saw-set is very simple in construction, and can be used for large and small saws, and will produce an even set, and at any angle desired.

Having thus fully described the operation and construction of my invention,

What I claim as new, and desire to secure by Letters Patent, is—

1. A saw-set, composed of the independent levers C and D, said lever C pivoted or hinged to the die b, supported at the rear by the chain-links h h, and ears or projections g g, to receive the lever D, all arranged to operate as and for the purpose described.

2. The lever-bars or handles A B, said lever B provided with ears g g, in combination with the independent levers C D, when arranged to operate as and for the purpose described.

3. The springs i j, when arranged in combination with levers A B C D, to operate said levers independent of each other, as and for the purpose set forth.

DANIEL AGNEW.
